(57) CLAIM

The ornamental design for a takeout food container, as shown and described.

DESCRIPTION

FIG. 4 is a bottom plan view of the takeout food container in an open position;

FIG. 5 is a front elevational view of the takeout food container in an open position;

FIG. 6 is a rear elevational view of the takeout food container in an open position;

FIG. 7 is a right elevational view of the takeout food container in an open position;

FIG. 8 is a left elevational view of the takeout food container in an open position; and,

FIG. 9 is a perspective view showing the front, top, and right sides of the takeout food container in a closed position with chopsticks inserted into the open tabs on top of the box that form handles for the user.

The broken lines illustrate environmental structure and form no part of the claimed design.

1 Claim, 9 Drawing Sheets
